UNITED STATES PATENT OFFICE

94,048

DESIGN FOR AN AUTOMOBILE GEAR SHIFT LEVER KNOB

Charles C. Puckett, Harlingen, Tex.

Application September 13, 1934, Serial No. 53,280

Term of patent 7 years

To all whom it may concern:

Be it known that I, Charles C. Puckett, a citizen of the United States, residing at Harlingen, in the county of Cameron, and State of Texas, have invented a new, original, and ornamental Design for Automobile Gear Shift Lever Knobs, of which the following is a specification, reference being had to the accompanying drawing, forming part thereof.

Figure 1 is a top plan view of an automobile gear shift lever knob, showing my new design,
Figure 2 is a side view in elevation, and
Figure 3 is a bottom plan view.

I claim:

The ornamental design for an automobile gear shift lever knob, as shown.

CHARLES C. PUCKETT.
